UNITED STATES PATENT OFFICE.

PERCY D. HAGAN, OF UNIONTOWN, PENNSYLVANIA.

SOCK.

1,330,315.

Specification of Letters Patent.

Patented Feb. 10, 1920.

Application filed July 8, 1918. Serial No. 243,867.

To all whom it may concern:

Be it known that I, PERCY D. HAGAN, a citizen of the United States, and a resident of Uniontown, in the county of Fayette and State of Pennsylvania, have invented certain new and useful Improvements in Socks, of which the following is a specification.

- This invention relates to socks or stockings, and an object of the invention is to provide a sock or stocking formed of two pieces, namely a leg portion and a toe portion, the meeting ends of which portions are provided with contracting cuffs to permit their connection.
- 15 An object of the invention is to provide a two piece sock, which will adjust itself to properly fit the foot of the wearer, and consequently decrease the liability of the wearing of holes in the toes of the socks, as well as eliminating the necessity of having various sizes of socks, since the socks will adjust themselves to various size feet within certain limits, and a retailer therefore could carry only a few different sizes of socks, the ordinary size and half sizes being eliminated in the manufacture of the socks.
- 20
- 25

Should the toe portion of the sock or stocking become worn, it could be replaced at a relatively small cost, and the sock or stocking would not need to be thrown away or darned in such instances, as new toe portions could be worn with the leg covering portion.

Other objects of the invention will appear in the following detailed description, taken in connection with the accompanying drawing, forming a part of this specification, and in which drawing:

Figure 1 is a side elevation of the leg portion of the sock.

Fig. 2 is a side elevation of the toe portion of the sock.

Fig. 3 is a fragmentary section through the foot portion of the sock showing the leg and toe portions connected.

Referring more particularly to the drawing, 1 indicates the main body portion of the sock, which has the usual type of contracting cuffs 2 at the upper open end of the same to cause the sock to cling to the leg of the wearer. The main body 1 includes the leg or ankle incasing portion 3 and the foot incasing portion 4 which latter has its outer end open and also has a cuff 5 formed thereon which is knitted in such manner as to provide a contracting cuff to snugly fit the foot of the wearer. This cuff

5 is knitted in the ordinary manner of knitting contracting cuffs, such as by purling. The cuff 5 is positioned for engaging over 60 or about the instep portion of a wearer's foot and it is also adapted for positioning within a contracting cuff 6 formed upon the detachable toe portion 7 of the sock. The cuff 6 of the toe portion 7 is knitted 65 or formed in the same manner as the cuff 5 so that when it is placed over the cuff 5 as shown in Fig. 3 of the drawing, it will contract and fit snugly about the outer surface of this cuff, holding the detachable toe 70 portion 7 securely upon the foot of the wearer. The yieldable connection between the toe portion 7 and the foot portion 4 of the body 1 of the sock will permit the sock to automatically adjust itself to different 75 size feet, thereby eliminating the necessity of the manufacturing of the sock in a number of sizes as well as materially decreasing the liability of wearing holes in the toe portion of the sock.

Having described the invention, what is claimed is:

1. As a new article of manufacture, a sock or stocking comprising a main body including an ankle inclosing portion and a foot 85 portion, and a detachable toe portion adapted to be connected to said body portion.

2. As a new article of manufacture, a sock or stocking comprising a main body including an ankle inclosing portion and a 90 foot portion terminating in a contracting cuff, and a detachable toe portion adapted to be connected to said body by means of said contracting cuff.

3. As a new article of manufacture, a sock 95 or stocking comprising a main body, having a foot portion, terminating in a contracting open ended cuff, a detachable toe portion, a contracting cuff formed upon the inner end of said toe portion for yieldable 100 engagement with the contracting cuff upon the body portion to detachably connect the toe portion to the body portion of the sock or stocking.

4. As a new article of manufacture, a 105 sock or stocking comprising a main body portion and a toe portion, said toe portion having a contracting cuff formed upon its inner end for yieldable engagement with the body portion to detachably connect the 110 toe portion to the body portion of the sock or stocking.

PERCY D. HAGAN.
